UNITED STATES PATENT OFFICE

WILLIAM A. UTTZ, SR., OF CLEVELAND, OHIO, ASSIGNOR, BY MESNE ASSIGNMENTS, TO
PERFECTION PACKAGE SEALER COMPANY, A CORPORATION OF TEXAS

UNDERCOUNTER SEALER

Original application filed March 4, 1927, Serial No. 172,712. Divided and this application filed September 11, 1929. Serial No. 391,842.

This invention relates to gummed tape dispensing machines and is a division of my prior application 172,712, filed March 4, 1927.

One important object of the invention is to provide an improved arrangement of gummed tape dispensing machine wherein the tape is normally prevented from engaging with the moistener by certain novel arrangements of delivery means. 5
10 A second important object of the invention is to provide an improved arrangement of gummed tape dispensing machine wherein tape may be fed forward from the machine to a desired extent without touching the tape 15 with the fingers.

A third important object of the invention is to provide a novel and improved arrangement of means whereby the tape will be constantly engaged frictionally by the delivery 20 mechanism.

A fourth important object of the invention is to provide an improved construction of gummed tape dispensing machine adapted especially for support beneath a store counter 25 or the like.

With the above and other objects in view as will be hereinafter apparent, the invention consists in general of certain novel details 30 of construction and combinations of parts hereinafter fully described, illustrated in the accompanying drawings and specifically claimed.

In the accompanying drawings like characters of reference indicate like parts in the 35 several views, and:

Figure 1 is a side elevation of the improved machine adapted for support beneath the top of a store counter or shelf.

Figure 2 is an end view of this machine.

40 Figure 3 is a detail section on the line 3—3 of Figure 2.

Figure 4 is an end view showing a modified means for supporting the machine slidably beneath a counter.

45 Figure 5 is a perspective view of a certain moistener and tape guide as used herewith.

Figure 6 is a perspective view of a spring plate forming a portion of this guide.

50 Figure 7 is a section on the line 7—7 of Figure 3.

Figure 8 is a section on the line 8—8 of Figure 1.

In the embodiment of the invention here shown there is provided a casing 10 forming a water tank and the rear of this casing is 55 covered by a closure 11. Mounted toward the forward end of the closure is a pair of L-shaped brackets 16 and in the upper end of these brackets is journaled the shaft 17, the journal ends of this shaft projecting laterally beyond the brackets on each side and preferably being covered with friction rings 18 of rubber or the like. This shaft 17 carries a tape feeding roller 19 which contacts with a plate 20 supported in a well 21 formed 60 in the closure 11. The plate 20 is pressed upwardly toward the roller 19 by suitable springs 22 so that paper or gummed tape passing between the feed roller 19 and the presser plate 20 will be forced 65 frictionally against the roller 19. At the rear end of the machine there is provided a roll support which includes a base plate 23 extending transversely of the machine and provided at each side with upwardly and laterally extending flanges 24 secured to the counter C by screws 25 so that the base plate 23 is held in position thereby. At each side of the center of the machine this base plate is 70 provided with a series of spaced slots 26 and supported from the base plate are standards 27 each having a Z-shaped foot 28 so that the respective standard may have its foot engaged in any one of the slots 26 and be held in a vertical position. In order to prevent 75 accidental tilting and disengagement of the standards 27 there is provided above the base plate 23 a spring presser plate 29 which is urged downwardly by springs 30 surrounding 80 guide pins 31 as shown. The plate 29 engages the upper sides of the feet 28 and thus holds the standards 27 from accidental tilting. These standards are provided with slots 32 for the reception of the center pin 33 of a roll 85 34 of gummed tape.

On the closure 11 is fixed a pair of spaced guide bars 39 of L-shape with their horizontal legs extending from each other. Seated between the guide bars 39 are other angle bars 40 which are preferably termed the pull 90 95 100

bars. In order to normally hold these angles 40 in rearward position there is provided at each side of the device a tension spring 46 one end of which is connected to a bar 40 and the rear end of which is secured to a lug 47. The angle bars 40 pass beneath the journal ends of the shafts 17 and engage the friction bands 18. The ends of the bars 40 are connected by a hand grip 49 so that they can be drawn forwardly together. The angle bars 40 have an up and down motion at their front and may be lifted to obtain firm engagement between the members 40 and 18. When thus engaged and drawn forward by the hand grip 49 the shaft 17, and consequently the feed roller 19 will be rotated and the gummed tape fed forwardly beneath this feed roller. It is to be observed that the rolls of gummed tape in some instances have the gummed side inwardly of each rear end and in other instances outwardly. In the operation of the machine with inwardly gummed tape the tape is fed off the upper part of the roll as shown in Figure 1 but, if the tape be gummed on the outer side, it will naturally be fed off of the lower part of the roll. It will be obvious that because the feed roll 19 is of larger diameter than the friction bands 18 the amount of tape fed forwardly will be in the same ratio to the forward movement of the angle bars 40, which may be termed for convenience feed bars, as the diameters of the friction band 18 and feed roller 19. In front of the device there is provided a lower guide plate 68 preferably of spring metal and having an upturned forward end provided with said guide lugs 69. Spaced above this is an upper guide plate 70 which has a forward edge 71 which is preferably serrated.

The moistening device is indicated in general at 72 and may be the same type as shown in my copending application above referred to but it is to be noted that the moistening device is so positioned that normally the extremity of the tape which projects from between the plates 68 and 70 does not contact with the moistening device but may be pressed down thereon as the tape is fed off.

For supporting the invention beneath a counter or the like the casing is provided with L-shaped hangers 72' which engage in guide bars 73 secured beneath the counter and there may be either two individual guide bars as shown in Figure 2 or there may be a single plate 74 having its edges bent to form channels 75 as shown in Fig. 4.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to in-

clude all such as properly come within the scope claimed.

Having thus described the invention, what is claimed as new, is:

1. In a gummed tape dispensing machine, 70 a counter, a pair of spaced guide members secured beneath the counter, a dispensing mechanism including a casing having supporting means slidably engaging said guide members to move in and out beneath said counter and means to feed the tape through the casing, and an upwardly extending actuating member operatively connected to the tape feed of the dispensing mechanism and arranged to lie to the rear of the counter. 80

2. In a gummed tape dispensing machine, 85 a counter, a pair of spaced guide members secured beneath the counter, a dispensing mechanism including a casing having supporting means slidably engaging said guide member to move in and out beneath said counter and means to feed the tape through the casing, an upwardly extending actuating member operatively connected to the tape feed of the dispensing mechanism and arranged to lie to the rear of the counter, 90 and a gummed paper roll support located to the rear of said movable casing and free therefrom.

3. The combination with a support of 95 counter like form; of a gummed tape dispensing machine supported thereby to move in and out beneath the support and including an operating member for causing the dispensing machine to dispense gummed tape and projecting upwardly behind the support in position to be grasped by a user. 100

4. The combination with a support of 105 counter like form; of a gummed tape dispensing machine supported thereby to move in and out beneath the support and including an operating member projecting upwardly behind the support in position to be grasped by a user, said machine including a water reservoir constituting a base for the operating mechanism. 110

5. The combination with a support of 115 counter like form; of a gummed tape dispensing machine supported thereby to move in and out beneath the support and including an operating member projecting upwardly behind the support in position to be grasped by a user, and a carrier for a 120 gummed tape roll depending from the support to the rear of the movable machine.

6. The combination with a support of 125 counter like form; of a gummed tape dispensing machine supported thereby to move in and out beneath the support and including an operating member projecting upwardly behind the support in position to be grasped by a user, said machine including a water reservoir constituting a base for the operating mechanism, and a carrier for a 130

gummed tape roll depending from the support to the rear of the movable machine.

7. In a machine of the kind described, a counter like support, a pair of guide rails fixed therebeneath in spaced relation and extending from one edge of the support inwardly thereof, a casing forming a water receptacle and having side walls extending above the casing top and provided with flanges engaging in said guide rails whereby the casing may move in and out beneath the support, and tape dispensing mechanism carried by the casing and arranged in the space between the support and the casing top.

8. In a machine of the kind described, a counter like support, a pair of guide rails fixed therebeneath in spaced relation and extending from one edge of the support inwardly thereof, a casing forming a water receptacle and having side walls extending above the casing top and provided with flanges engaging in said guide rails whereby the casing may move in and out beneath the support, and tape dispensing mechanism carried by the casing and arranged in the space between the support and the casing top, said mechanism including an operating handle extending upwardly in spaced relation to the rear edge of the support.

9. In a machine of the kind described, a counter like support, a pair of guide rails fixed therebeneath in spaced relation and extending from one edge of the support inwardly thereof, a casing forming a water receptacle and having side walls extending above the casing top and provided with flanges engaging in said guide rails whereby the casing may move in and out beneath the support, tape dispensing mechanism carried by the casing and arranged in the space between the support and the casing top, and a carrier for a gummed tape roll depending from the support to the rear of the movable machine.

10. In a machine of the kind described, a counter like support, a pair of guide rails fixed therebeneath in spaced relation and extending from one edge of the support inwardly thereof, a casing forming a water receptacle and having side walls extending above the casing top and provided with flanges engaging in said guide rails whereby the casing may move in and out beneath the support, tape dispensing mechanism carried by the casing and arranged in the space between the support and the casing top, said mechanism including an operating handle extending upwardly in spaced relation to the rear edge of the support, and a carrier for a gummed tape roll depending from the support to the rear of the movable machine.

In testimony whereof I affix my signature.
